RENÉ LOUIS MAXIME BELLEAUD AND JEAN BARROLLIER, OF COURBEVOIE, FRANCE.

MERCURY ELECTRIC LAMP.

Application filed December 16, 1920. Serial No. 431,104.

To all whom it may concern:

Be it known that we, RENÉ LOUIS MAXIME BELLEAUD and JEAN BARROLLIER, both citizens of the Republic of France, both residing at Courbevoie, Seine, France, have invented certain new and useful Improvements in Mercury Electric Lamps, of which the following is a specification.

The majority of mercury vapor lamps heretofore constructed present various defects. In the operation of the lamp there occurs a transfer of mercury from the anode to the cathode. This is due mainly to the anode being at a higher temperature than the cathode so that the mercury distils from the anode towards the cathode. Moreover, by reason of the difference of temperature between the anode and the cathode, it sometimes happens that the anode is subjected to excessive heating, whilst the cathode is at a temperature too low to permit a sufficient vaporization of the mercury and a high output from the lamp in visible and ultra-violet radiations. In fact, if the cathode is too cool, the result is a general cooling of the arc, and it is well known that the smaller its heat the poorer it is in ultra-violet radiations.

These several defects result from the difference in temperature between the points of the anode and of the cathode from which the electric arc is formed.

Our present invention consists in an improved mercury or amalgam vapor lamp, in which the temperatures between the anode and the cathode are equalized, permitting the lamp to be operated under high voltage, without an appreciable transfer of mercury from the anode to the cathode occurring and without any of the components of the lamp being raised to a temperature liable to alter such conditions.

Our improved lamp has a mass composed of a certain variety of substances, conductors of heat and separate from the mercury or amalgam constituting the electrodes, the said mass surrounding such electrodes, preferably in the immediate neighbourhood of the point from which the arc is generated, thereby ensuring an interchange of heat between the electrodes. This mass thus constitutes an equalizer of temperature between the two electrodes. Moreover, the said mass stores up a certain amount of heat and therefore serves as a regulator or balancer

of temperature for both electrodes. Consequently, shortly after the formation of the arc, a state of calorific equilibrium is established, which prevents, or at least reduces to a large degree, the transfer of vapour tending to be set up from the anode to the cathode.

Moreover, the mass, by abstracting heat at the anode, prevents its being excessively heated and in transmitting such heat to the cathode, assists the metallic vaporization at the contact of such cathode, which increases the output of the lamp in visible and ultra-violet radiations.

Embodiments of the lamp in accordance with our invention are shown, by way of example, on the annexed drawing, on which Fig. 1 is a longitudinal section through a lamp; Fig. 2, a perspective view of a set of two such lamps; Figs. 3-5 illustrate various other embodiments of our invention.

The illuminating tube 1, in which the arc plays, is bent in such a manner that the points of starting and arrival of the arc at the electrodes 2 and 3 are in proximity to one another.

A container 4 is welded around the electrodes. This container is partially filled by a substance or a mixture of substances 5, conductors of heat, e. g. mercury, or any other suitable conductor of heat. This substance is introduced by a neck 6 which is afterwards sealed.

The substance 5 thus serves as a temperature regulator and temperature equalizer between the two electrodes.

A similar container such as 4, may be common to several mercury lamps as shown in Fig. 2 wherein is shown a set of two mercury lamps 1, which have a common container 4.

The container 4 may assume any suitable shape, and the mass 5 therein may be any suitable substance or mixture of substances. The only requisite is that the mass possess a certain calorific conductivity enveloping the two electrodes and ensuring a sufficient interchange of heat between them. Thus, instead of arranging a container 4 common to the two electrodes, two separate containers 7, 8 (Fig. 3) can be provided each surrounding an electrode 2, 3 but interconnected by connectors of good heat conducting material, such as metal rods 9, good heat conducting liquid, etc. Also, the mass may

consist of a series of wires 10 (Fig. 4) or a metal envelope, enclosed as a core or not in any suitable kind of matrix 11, or even of a mass of quartz or porcelain 12 (Fig. 5) uniting the electrodes.

Our invention thus enables the generation of intensive arcs of high output, without material transfer of mercury from the anode to the cathode, the lamps being of simple construction, compact dimensions and great durability, as none of the parts is raised to an excessive temperature.

And these lamps can have anodes and cathodes which are alike, which simplifies their construction and use.

We claim as our invention:

1. In a metal vapor lamp, the combination with the illuminating tube and the spaced electrodes, of a heat conductive regu-

lating mass secured to and surrounding the 20 said electrodes.

2. A metal vapor lamp as specified in in claim 1, in which the said regulating mass surrounds the electrodes in the immediate vicinity of the points of departure and ar- 25 rival of the arc.

3. In a metal vapor lamp, the combina- 30 tion with the illuminating tube and the spaced electrodes, of a casing surrounding the electrodes and secured thereto forming a unitary structure therewith, and a mass of heat conducting material in said casing constantly maintaining the electrodes at equal temperatures.

In testimony whereof we have affixed our 35 signatures.

RENÉ LOUIS MAXIME BELLEAUD.
JEAN BARROLIER.
